ATTORNEY

UNITED STATES PATENT OFFICE.

FRANCIS F. PARSONS, OF PATERSON, NEW JERSEY, ASSIGNOR OF ONE-HALF TO ALFRED SCHIFFER AND HERMAN SCHIFFER, OF PATERSON, NEW JERSEY.

REMOVABLE PIPE-BRACKET.

SPECIFICATION forming part of Letters Patent No. 703,454, dated July 1, 1902.

Application filed September 20, 1900. Serial No. 30,564. (No model.)

To all whom it may concern:

Be it known that I, FRANCIS F. PARSONS, a citizen of the United States, residing in the city of Paterson, county of Passaic, and State 5 of New Jersey, have invented certain new and useful Improvements in Removable Pipe-Brackets; and I do hereby declare the following to be a full, clear, and exact description of the invention, such as will enable others 10 skilled in the art to which it appertains to make and use the same, reference being had to the accompanying drawings, and to letters of reference marked thereon, which form a part of this specification.

15 I have in the invention presented in this description had for my object the construction of a removable supporting means for pipes. It is a well-known fact that more or less trouble has existed and exists still in 20 the securing of the brackets firmly into the wall, and consequently whenever occasion demanded it to release the said pipes—for instance, during repairs or in case of fires or other accidents. As a consequence the main 25 point that I have sought to improve on in my present invention is to provide a means separate from the bracket itself that can be removably secured therein.

In describing my invention I shall call attention to the accompanying drawings, wherein like letters of reference indicate corresponding parts in the different views.

30 Figure 1 is a front view of my improved bracket or, as will be known in the specification, the "holder." Fig. 2 is a side view of the said holder, showing the plate carrying the hooks in its operative relation to the holder. Fig. 3 is a front view of the removable sliding part that supports the pipes. 35 Fig. 4 is a side view of said sliding part; and Fig. 5 is a sectional top view on lines $x-x$ through Fig. 2, showing the two parts in combination with each other.

40 In the figures, A indicates the holder. Said holder is provided with lugs B', B², B³, B⁴, B⁵, and B⁶. On the back or rear part of said holder there is at both the top and bottom a circular boss, which are lettered, respectively, C' and C². Said circular bosses stand out or 45 project from the top and bottom of the rear

of the main body of the holder, as observed in Fig. 2, while the lugs B' to B⁶ project in front. The bosses C' and C² are provided with recesses C³, extending into said bosses and apertured at C⁴ for the reception of fastening means. The lugs B' to B⁶ being made integral with the holder form spaces G, as best observed in Fig. 5, into which spaces, between the lugs B' to B⁶ and the main body of the holder, the bracket K is introduced. 55 As seen in Figs. 1 and 2, the bottom of the body terminates in a shelf or rest I, projecting toward the front, on which rest or shelf the bracket K will rest when slid down from the top primarily between the lugs B' and B⁴. This bracket K is furnished with hooks or supports J', J², J³, J⁴, and J⁵ or any other adequate number, which hooks are either cast as parts of the body of the bracket or are otherwise fittingly attached to said 60 body. Finally in these hooks the pipes L', L², L³, L⁴, and L⁵ are placed, such pipes consequently being easy removable by lifting them out of their respective hooks or supports. It can now readily be seen from the 65 foregoing that after the holder A has been secured to the wall the bracket K is slid down between the guides B' to B⁶ and the body, whereupon the pipes L' to L⁵ are deposited 70 in their respective supports J' to J⁵.

In conclusion I may state that it does not affect the validity of my invention how many hooks the bracket K is fitted with or what kind of material my removable pipe-bracket is attached to and that, further, my direct- 75 attachment means—that is, what I term the "holder" A—can be successfully used for other brackets than, for instance, for supporting pipes.

What I consequently claim in accordance 80 with the above description, and desire to secure protection for by Letters Patent, is—

1. In a pipe-hanger, the combination of a holder, consisting of a plate provided on one side with a boss and on the other with a recess extending into the boss, said boss being apertured for the reception of fastening means, with a bracket consisting of a plate provided with a hook, the structure of the holder and bracket being such that the latter 85 90 95 100

is adapted to be held removably in place against the holder so as to cover the recess therein.

2. In a pipe-hanger, the combination of a holder, consisting of a plate provided at one side with one or more bosses and on the other with recesses extending into said bosses, said bosses being apertured for the reception of fastening means, lugs on the side and bottom of said holder and cast integral therewith to receive and support the bracket, with a bracket consisting of a plate provided with

hooks, the structure of the holder and bracket being such that the latter is adapted to be held removably in place against the holder so as to cover the recesses therein.

In testimony that I claim the foregoing I have hereunto set my hand this 29th day of August, A. D. 1900.

FRANCIS F. PARSONS.
